UNITED STATES PATENT OFFICE.

LOUIS N. MOSS, OF NEW YORK, N. Y.

DESIGN FOR AN ASH-TRAY.

SPECIFICATION forming part of Design No. 34,472, dated May 7, 1901.

Application filed April 10, 1901. Serial No. 55,267. Term of patent 3½ years.

To all whom it may concern:

Be it known that I, LOUIS N. MOSS, a citizen of the United States, and a resident of New York, county of New York, and State of New York, have invented and produced a new and original Design for Ash-Trays, of which the following is a specification, reference being had to the accompanying drawing, forming a part thereof, in which similar letters of reference indicate corresponding parts.

As shown in the accompanying drawing, the leading or material feature of my design consists of a frying-pan A, having a lip a^3 and a handle A'. The pan is circular in contour and has tapering sides, and between the pan and the handle is a triangular portion B, with two of its sides extended tangentially from the periphery of the upper edge of the pan. The handle A' has edges which describe compound curves connected at the free end of said handle by a semicircular line a^2 . The said handle also has a convex upper surface

at a^3 and is provided with a circular opening a^4 .

Upon the upper surface of the pan-bottom 25 is a circular shield C, having stars c and stripes c' upon its surface, and also a representation of a buffalo D.

An angular recess b is formed in the portion B and which has rounded edges b' and 30 a flat bottom b².

Having described my invention, what I claim as new, and desire to secure by Letters Patent, is—

The design for an ash-tray, as herein shown 35 and described.

In testimony that I claim the foregoing as my invention I have signed my name, in presence of two witnesses, this 1st day of April, 1901.

LOUIS N. MOSS.
